Application March 20, 1937, Serial No. 132,050
In Germany April 4, 1936

1 Claim. (Cl. 250—36)

It is well known to associate oscillatory circuits with means whereby the frequency thereof shall be independent of the temperature of the surrounding medium. This is generally attained by effecting a compensation for the variations in capacity and inductivity which entail a frequency change of the oscillatory circuit. In some cases however, especially if arrangements for very high frequencies are concerned, difficulties arise through a frequency change which is independent of the temperature of the surrounding medium. This special frequency change may occur for instance with discharge tubes of the kind having a glowing-cathode and one or more additional electrodes, being caused here by the inter-electrode capacities varying when the tube is heated up. Such capacity variation will cause a frequency change of the oscillatory circuits in which tubes of this kind are included.

The invention has for its object to avoid these difficulties and to such end provides for compensating the said special frequency change in a peculiar manner, as will be understood from the following description and be particularly pointed out in the appended claim, reference being had to the accompanying drawing that shows an example of a circuit arrangement as provided by the invention.

The example illustrated is a feed-back connection and comprises a tube E that has three electrodes one of which is a glowing-cathode C. When heating up this tube the inter-electrode capacities, that is, the capacities between cathode C, grid and anode, undergo variation. In the case of an indirectly heated tube, for example, this variation is such that after a certain time, for instance 20 minutes, a definite value of the inter-electrode capacities is reached.

In the example here disclosed the variation in the inter-electrode capacities is compensated by a variable additional capacity connected in parallel with the inter-electrode capacities and constituted by a condenser that consists of a metal plate A and a bimetallic strip or spring B. Plate A is connected to the anode, as shown. Spring B is heated by a coil H connected in parallel with cathode C. Hereby the distance between A and B and thus the additional capacity connected in parallel with the inter-electrode capacities is so varied that a variation of these is compensated and that therefore a frequency change of the oscillatory circuit pertaining to tube E will not occur. Spring B is disposed in a jacket or any other casing or envelopment J made of a material which is a non-conductor of heat. By this means spring B is given a time constant which is equal to that of tube E, that is to say, the final capacity value of spring B is reached in the same time as that of tube E.

What is claimed is:

An oscillatory circuit including a glowing cathode tube and means associated therewith for opposing frequency changes resulting from changes in the constants of said tube during operation thereof comprising a condenser connected directly between the anode and cathode of said tube, a bi-metallic strip having an electric heating element connected in parallel with said cathode for varying the capacity of said condenser and a heat insulating jacket surrounding said strip and said heating element, said jacket being so proportioned that the final value of capacity of the said condenser as controlled by said bi-metallic strip is reached at the same time as the final capacity of said tube upon heating up of said circuit.
